APPARATUS FOR MAKING GREETING CARDS

Goldie Jacobs Klein and Benjamin Klein,
Long Island City, N. Y.

Application June 15, 1944, Serial No. 540,434

17 Claims. (Cl. 93—1)

1

This invention relates to an apparatus utilized in the fabrication of greeting cards, especially of cards having a portion or portions arranged to extend in different vertical and horizontal planes when erected, thus yielding desirable effects of depth and perspective, and more particularly of cards of the above type in which the operation of erection of the card is effected by drawing upwardly upon a suitable portion of the card, whereby the various vertical and horizontal elements are caused to assume their intended relative positions.

The instant application is a continuation-in-part of our pending application Serial No. 420,932, filed November 29, 1941, which has matured into Patent No. 2,415,501.

For the sake of economy in the fabrication of these articles, and speed in their production, it is desirable to make each card, with all its component parts, by cutting and creasing an integral blank of sheet material of suitable shape and dimensions, thus rendering it unnecessary to make separately, and paste on, any parts essential to the completion of the structure. Heretofore, except in the case of very simple articles of the class described, it has not been found possible to produce satisfactory one-piece greeting cards of the type indicated.

A difficulty encountered heretofore in the fabrication of these greeting cards, erected from cut and creased blanks, is that it has been necessary to "break" by hand the creased portions in order that they may respond readily to the operation of erecting the completed article, without special training or skill on the part of the recipient of the greeting card, who is usually of somewhat less than average mechanical aptitude, since these greeting cards have a large sale as gifts for very young persons.

It will be understood readily that the time necessary to "break" carefully the creases in a large quantity of such cards, in the course of their manufacture, each having numerous creases, will slow down quantity production and increase the cost to an inordinate extent, and the provision of apparatus for the elimination of this manual operation is the primary object of the present invention.

Ancillary to this object is the provision of co-operative movable dies or templates, constructed and arranged to effect the "breaking" of all the creased regions in a greeting card of the type under consideration, as a single step in the fabrication of the card, and to this end to provide a set of such movable dies or templates which are

2

durable in structure, adapted to effect the breaking step without injury to the cards, even when made of fragile material, and also to perform the operation in a reliable manner and at a desirable rate of speed.

Other objects and features of the invention will appear as the description of specific embodiments of our invention progresses.

In the drawings,

Fig. 1 is a view in front elevation of a greeting card produced by an apparatus in the construction of which the present invention has been embodied;

Fig. 2 is a plan view of the structure shown in Fig. 1;

Fig. 3 is a plan view of a cut and scored blank from which has been erected the greeting card shown in Figs. 1 and 2;

Fig. 4 is a view in vertical, longitudinal section, of a movable die or template assembly provided by the invention for "breaking" the blank shown in Fig. 3, and for erecting it to form the complete gift or greeting card shown in Figs. 1 and 2;

Fig. 5 is a vertical, longitudinal section through the movable die or template mechanism, showing the paper blank interposed between the sections of the die or template mechanism, and in dotted lines the position of the vertical portion of the mechanism when brought forward to its fullest extent to accomplish the breaking of the blank.

Fig. 6 is a plan view of the assembly of the die or template mechanism and intermediate blank after breaking.

Fig. 7 is a plan view of the base template piece with a portion of the superimposed paper blank cut away;

Fig. 8 is a top plan view of the assembly of template mechanism in the upright position thereof;

Fig. 9 is a detail fragmentary view of a portion of Fig. 6 showing opposition hinges of the template or die plates with the paper blank therebetween;

Fig. 10 is a section on the line 10—10 of Fig. 9;

Fig. 11 is a fragmentary detail of an improved and modified form of stop and gripper for the paper blank for use with a sheet having a straight edge, for instance, the page of a book, wherein no overhanging of the paper blank during breaking is feasible;

Fig. 12 is a section on the line 12—12 of Fig. 11 with the top template in place and the sheet to

be formed shown in position between it and the bottom template.

Fig. 13 is a perspective view of a frame and counterweight device for facilitating the use of the template mechanism; and

Fig. 14 is a plan view of the frame and counterweight mechanism of Fig. 13.

Referring now to the drawings in detail, the reference character 11 designates in general a complete greeting card constructed by the apparatus of the present invention and comprising what will be termed for the sake of brevity, a main structural panel element 12, having numerous integral parts which need not be described in detail, a base panel structural element 13, from which parts of the element 12 have been developed by cutting and creasing operations, a back structural panel element 14, from which other parts of the structure have been developed, being disposed at the rear of the upright element 12, and connected at a fold line 16 to the element 15. All of these elements are preferably constituted by integral parts of a blank of suitable sheet material 17, such as thin cardboard (see Fig. 3) somewhat resilient, and cut and creased to form the component elements and parts as herein disclosed.

In the greeting card shown in Figs. 1, 2, and 3, there are no parts other than those developed from the original blank, and all parts shown are held in position by virtue exclusively of their original suitably formed parts thereof bent into retentive engagement of a character designed to maintain the complete structure in its fully erected position, as shown in Figs. 1 and 2, without the use of adhesives.

In the blank shown in Fig. 3, as cut and creased suitably prior to its erection to the position illustrated in Figs. 1 and 2, a fanciful figure 18 is delineated, seated upon a throne. The main upright portion of the throne can be moved forward out of the plane of the panel 12, as clearly indicated in Fig. 2, this operation being effected in general by bending panel 12 up at right angles to panel 13, along the fold lines 19 therebetween.

The elements of the card shown in Figs. 1 and 3 and the operations on the crease or fold lines in producing the final effect of having a collapsible greeting card, are fully described in our aforementioned pending application and need not be herein more fully discussed.

As the specific greeting card shown is merely an illustrative form of a large variety of greeting card structures which we may produce by the apparatus of the instant invention, it should be understood that Figs. 1 to 3 are included in the present application only to illustrate the nature of the product capable of being operated upon by our apparatus, namely, an integral blank comprising all the structural components of the completely erected greeting card, whether or not including those to be disposed in numerous vertical planes and horizontal planes, with parts constructed and arranged to be engaged frictionally with other parts to constitute a self-retaining erected structure without the use of adhesive.

In the remaining figures of the drawings, are illustrated an apparatus, and its component parts for producing the finished greeting card of Figs. 1 and 2 from the blank of Fig. 3.

In pursuance of the invention, we provide the apparatus for breaking the blank of Fig. 3, and erecting the gift card structure.

Our novel blank "breaking" device comprises a movable die or template mechanism shown in jux-

taposed position of its parts in Fig. 4 and in vertical section in the course of its operation in Fig. 5. Such mechanism comprises a base piece or block 20 preferably made of wood, having a vertically extending boss 21 extending across its width near one end and to the upper surface of which base piece or block is secured the primary pattern flap 22 to which in turn is attached, by hinges 23-24, the movable primary pattern flap 25. To the under surface of the pattern flap 25 is secured a wood strip 26, the pattern flap 25 being capable of swinging about the hinges 23-24 through an angle limited by the length of a chain 27, one end of which is anchored by screw 28 to the upright boss 21 and the other end by screw 29 to the upper end of the wood structure 26. The height of the boss 21 is such that the angularity of the pattern flap 25 to the base block 20 when the wood structure 26 rests upon the boss 21, is approximately 30°.

Depending upon the design of the blank of paper to be "broken" by the movable template mechanism, the lower template unit comprises primary metallic design flap 22 connected to another primary flap 25 by a pair of hinges 23 and 24, and is provided with a plurality of secondary flaps 30 of the specific design of outline of the portions of the blank sheet to be broken, the various secondary flaps 30 at their lines of juncture with adjacent primary and secondary flaps being connected by means of hinges 31 which may be of metal, the hinges being riveted, in that case, to the flaps. The contour of these flaps is such that all the margins are slightly inside similar outlines of the design, as shown in Fig. 6. This is necessary, so that the flap portions of the lower template unit will pass through corresponding openings in the upper template unit in the forming process.

The upper template unit comprises a wood frame 32, to the under surface of which is secured primary metallic design flap 33 connected to another primary flap 34 by a pair of hinges 34. The upper template unit is also provided with a group of secondary flaps 35 connected, at their line of juncture with the primary and secondary flaps by hinges 36, the entire group of primary and secondary flaps registering with and resting on the flaps 22, 25, and 30 of the bottom template piece when the top template piece is superimposed upon the bottom template piece, with the blank sheet of material 37 positioned between the two template pieces. The contour of these flaps is such that all the margins are slightly outside similar outlines of the design. This is necessary so that the folding design of the sheet and the corresponding flap portions of the lower template unit will pass through the opening formed in the upper template unit by the flap portions of the upper template unit, moving out of their original planes when the forming process takes place.

The construction of both the lower and upper template units is such that in each one of the faces of the two primary flaps, i. e., 22, 25 and 33, 34, constitute two sides of projected parallelograms, with two faces of some of the secondary flaps 30 and 35 that are hinged directly to them and form the other two sides. The faces of all other secondary flaps constitute sides of projected parallelograms, either with two other secondary flaps, or with one primary and one secondary flap, and are hingedly attached, either to two secondary flaps, or to one primary and one secondary flap.

In the geometric construction of a parallelogram, opposite angles must always be identical. In the device of the present invention as shown in Fig. 4, the faces of all of the parallelograms, in the lower and in the upper template units, are parallel either to the horizontal primary flaps 22, 33 or primary flaps 25 and 34, that are 30° above a horizontal, when the device is not in use. Therefore, the equivalent angles of all of the projected parallelograms are identical. In as much as the angle of any projected parallelogram in our apparatus is changed there is accomplished an automatic change in the shape of all of such parallelograms.

When either a lower or upper primary template unit, or the combination of both of such units, is folded forwardly from its 30° starting point, previously described, the length of the sides of the projected parallelograms can not change, because such parallelograms are constructed of rigid material. The angles of the parallelograms, however, can be changed because the sides thereof are hingedly connected. When a paper blank which has been previously cut and scored as is shown at Fig. 3 is placed in position above the lower template unit, and the upper template unit is then laid over it, the weight of the upper template unit, plus a slight downward pressure by the operator of the device thereon, causes the yielding paper to conform to the same projected parallelograms as are assumed by the faces of the primary and secondary flaps. This conformation is the beginning of the breaking and forming pressure.

After the paper blank and the upper template piece have been superimposed upon the lower template piece, the upper edges of the two template elements are grasped in unison by the operator and pulled upwardly and forwardly, so as to have the flaps 25 and 34 pivot about their respective hinges 24 and 34' to the substantially upright position of the assembly of template pieces and blank imposed therebetween shown in Fig. 5 and then forwardly to an extent indicated in dotted lines in Fig. 5 and limited by the length of the chain 27. In addition to the limiting of the forward movement of the template piece by the chain 27, there may be provided a pair of stop blocks 44 extending upwardly from the base piece 32.

This upward and forward movement of the two template pieces with the paper blank embraced therebetween will effect the "breaking" of the paper blank, along the various fold and score lines delineated by the cooperating flaps 30 and 35 of the respective template pieces.

The movement of the two sections of the upper template piece toward and away from each other about the hinges 34' is controlled by chain 38, one end of which is anchored in the frame 32 and the upper end of which is anchored in the upper frame section 32'.

For the purpose of guiding the positioning of the upper template piece for exact superposition of its flaps and the paper blank upon the upper surface of the lower template piece in absolutely correct position relative to the flaps of such lower template piece, the following guide members are provided.

The base piece or block 20 of the lower template element is provided with two upright anchor irons 40, 40, the distance between which is exactly the width of the paper blank to be broken by the mechanism. Extending from the upper extremities of the base of the lower template piece at each

upper corner is a pair of extensions 41, 41, having rounded corners at 42 which are similarly spaced the exact distance of the width of the paper blank to be positioned upon the template piece. The upper extremities of the upper template piece are provided with two anchor irons 43, 43, the legs of which fit exactly into the space between the extensions 41, so that when the upper template piece is superimposed upon the lower template piece after the paper blank has been placed upon the latter, the upper template piece will be exactly positioned by the cooperating engagement of the two extensions 41 by the anchor irons 43 and at the lower end of the template assembly by the proper positioning of the upper template structure intermediate the two anchor irons 40 extending upwardly from the lower template piece.

Prior to the superposition of the upper template piece upon the lower, the paper blank 37 is placed upon the lower template piece with the straight edges of the paper blank between the extensions 41, the paper blank extending downwardly between such extensions as shown in Fig. 4.

In Figs. 11 and 12, we have illustrated a construction of the upper portion of the lower die or template unit which is to be used in forming or breaking blank sheets which have a straight top edge, for instance, the page of a book, rather than one which has an overhanging portion as in the greeting card illustrated in Figs. 1 to 3.

By an overhang we mean the portion of the blank sheet which in Figs. 4 and 5 is illustrated as overhanging the upper edge of the die or template units when the breaking of the sheet is being effected. Without such overhanging portion of the blank the lower die or template unit is to be constructed in accordance with the embodiment illustrated in Figs. 11 and 12.

In such embodiment, the upper portion of the lower die or template unit is shown with its slots 45 limiting the downward movement of the upper section of the former and therefore of the sheet. The lower die or template unit is provided with a longitudinal slot 46, the metal of the die or template unit being bent slightly backwardly and below the surface, as at 47, so as to act as a frictional grip for the blank sheet being placed upon the unit.

The blank sheet 48 is placed upon the surface of the unit and pushed upwardly until the upper edge thereof abuts the upper edge of the slot 46 with the bent-under portion of the paper being pressed downwardly to a position below the upper surface of the remainder of the sheet. The sheet along its upper edge on each side of the downwardly bent portion 47 abuts against the top guide sections 49, 49.

The lower edge of the slot 46 opposite the bent downwardly portion 47 is similarly bent backwardly and downwardly at 50 slightly more than the degree to which the edge 47 is bent backwardly and downwardly. This bending backwardly and downwardly of the edge 50 of the metal is facilitated by the provision of slight cut-outs 51 and 52.

The paper blank being thus positioned upon the lower former unit and abutting against the top guides 49 and positioned under the bent edge 47, the upper die or template unit is placed over the blank sheet and the lower die unit, and when the two sections of the former unit are brought forward, as heretofore described, the blank sheet is automatically brought to a position in which it is no longer in abutting relation with the top guides 49 but assumes a

position in which its top edge is in alignment with the lower edges of the slots 45.

In Fig. 12 we have shown the position of the blank sheet 48 with the upper edge thereof entering into the slot 46 and abutting the bent downwardly edge 47, such upper edge of the paper sheet being brought down after the super-position of the upper die or template unit in the operation of breaking the sheet to a position in which it is shown in Fig. 11.

It will be noted that when the blank sheet is being formed by the two units of the former apparatus being brought forward, the sheet being operated upon rides freely in the distance between the edges of the top guides 49 and the edges of the slots 45, but that during the upwardly or return movement of the die units, the paper, instead of going back under the bent edge 47, can ride over it. Thus when the operation is completed the sheet can be readily removed because it is no longer gripped under edge 47.

In Figs. 13 and 14 is shown a scaffold and counterweight arrangement for facilitating the utilization of an apparatus embodying our invention. With such arrangement, the two movable die or template pieces are incorporated in a supporting structure in such manner that the horizontal portion of the scaffold supports the bottom movable die or template piece and the upper movable die or template piece is suspended from the vertical section of the scaffold.

In the operation of the breaking apparatus embodying the two movable die or template pieces as shown in Figs. 4 and 5, the operator is required to remove the upper movable die or template piece from its superposed position upon the lower movable die or template piece before a blank sheet which is to constitute the finished card is to be placed in position upon the lower template piece. The upper template piece is then necessarily picked up from its position upon a supporting surface to one side of the lower template piece and placed over the blank sheet and lower template piece. As the breaking of the blanks to constitute the finished card is done by an operator at a considerable and rapid pace, the necessity of removing and replacing the upper template piece for each operation is extremely tiresome to the operator.

We have, therefore, devised the scaffold and counterweight arrangement illustrated in Figs. 13 and 14, whereby the upper movable die or template piece, in order to place the blank sheet in position upon the lower movable die or template piece, need only be raised by grasping its forward edge to permit the counterweight, by means of which it is suspended from the scaffold frame, to do a substantial portion of the work of raising the upper template piece. The counterweight is so adjusted that a very slight initial movement is all that is necessary to be given by the operator to the upper die or template unit which then, by reason of the action of the counterweight, will be brought to a position in which it sufficiently clears the lower die or template unit to permit the operator to properly position the blank sheet upon the lower template piece and then by the slight downward pull upon the upper template unit, reposition such unit upon the blank now placed over the lower unit.

In such scaffold and counterweight arrangement, 60 designates the lower frame structure from the rear end of which extends upwardly the vertical frame structure 61. The two frames are held in right angular position by the side pieces 62.

Resting upon the horizontal bottom frame 60 is the lower die or template piece 63 which is substantially like the lower template piece of Figs. 4 and 5 having similar angles 40, back stop blocks 5, 24, and wood strips 26, upon which wood strips 26, near their upper ends are angle irons 64.

The upper movable die or template unit is constituted of side pieces 65 and front blocks 66 constituting a reinforcing means and a point of 10 anchor for the chains 67, 67 which are anchored at their opposite ends in blocks 68, 68.

On the outer face of each of the blocks 65 and, at a point nearer the hinge of the two halves of the upper template unit are positioned two eyelets 69 to which are tied the ends of cord 70 passing through pulleys 71 and secured by a pair of hooks 72 to a counterweight 73. The eyelets 69 are thus placed to one side of the median lines of the blocks 65, so that the counterweight, by 20 means of its cord 70, pulls against the back half of the template unit and thereby cause the chains 67 to be taut. The block 65, in addition to acting as a means for attaching the cords suspending the counterweight, constitute reinforcing means for the structure.

Extending upwardly from the rear edge of the lower template unit is a pair of pins or stops 74. When the top unit or template piece is raised in preparation for the sheets to be broken to be 30 inserted or positioned upon the bottom template, the upper rear edge of the top template abuts the two stops 74 of the bottom unit. By thus limiting the movement of the top template piece, its angle iron guides are kept in longitudinal alignment with the slots in the lower template piece. When the upper unit is lowered during the operation of the breaking of the blank there is, as shown in Fig. 13, a space between the stops 74 and the upper edge of the top template unit. 40 This arrangement permits the operator to lift the top template piece and place it down on, and parallel to, the blank, as shown in Fig. 4 and be sure he is working in proper longitudinal alignment.

The top template unit, on each side of the upper 45 edge thereof, is cut away as shown at 75 to permit the top element to pass the angle iron guides on the bottom unit and to place the top unit in proper longitudinal alignment with the bottom unit.

50 The complete former or breaking apparatus as shown in Figs. 13 and 14 makes possible the extremely rapid disengagement of the two movable die or template units from the intermediately disposed blank of sheet material, so as to remove such blank after it has been broken and to insert another blank or series of blanks to break and form another card unit.

The use of the scaffold and counterweight arrangement makes possible the fabrication of the 60 upper and lower movable die or template elements and their breaking flaps with sufficient body and rigidity to make possible the operation in breaking simultaneously of a plurality of sheets of superposed blanks of card material.

The specific embodiment of the scaffold and counterweight arrangement just described is, of course, merely illustrative. As its sole purpose is to facilitate the putting together and separating top and bottom template units; support and reinforce the metal elements; and to act as a stop of 30° under the bottom unit, when it is open, and as a stop of 45° on the upper surface of the top unit, when it is closed, any other arrangement, effecting substantially the same re-

suit, may be resorted to without departing from our invention.

We claim:

1. A device for breaking a cut and scored blank for a gift card or the like, and for bending said card along the fold lines thus provided, to a temporary, completely erected position in order to facilitate subsequent manual erection of the card to a like position by the user of the card, without the aid of said device, the latter comprising a template mechanism consisting of upper and lower movable units adapted to be assembled in substantially parallel superimposed relation with the originally flat blank, each of said units having an upper and a lower section, hingedly connected along a portion of their edges, the upper and lower sections of each unit being maintainable at a predetermined angle to each other, each unit containing a plurality of smaller hinged parts constructed and arranged in such manner that they always move with, and parallel one of the surfaces of the units with which they are integral, the two units, when superimposed with a cut and scored blank interposed between them, being foldable in unison along their horizontal medial line, and which, when a forward movement is imparted to their top edges, while their bottom edges are held almost rigid, effect the folding of the portions of the blank between the two units, the smaller hinged parts of such units, and the portions of the blank between the smaller hinged parts, the folding of all of such parts and portions being into planes parallel to the planes assumed by the upper and lower sections of the combined upper and lower units.

2. A device as claimed in claim 1, wherein the template mechanism includes in both of its units spaced guiding elements for maintaining the units, when superimposed with the originally flat blank therebetween, in exact cooperative relationship of their respective parts.

3. A device as claimed in claim 1, wherein the smaller flap-like parts provided on the template units are constructed and arranged to be superimposed one upon the other with the flat blank pressed between them, the movable units acting to break said blank by virtue of a complementary action thereon when the upper template unit is pressed toward the lower template unit, with the hinged parts thereof moving the corresponding portions of the blank out of their original plane.

4. A device as claimed in claim 1, wherein the template units have transverse hinges about which a substantial portion of each of said units may be swung, the smaller hinged parts being so constructed and arranged that by lifting a portion of the template units about said transverse hinges thereof, said smaller hinged parts will be caused to project from the planes of the units to an extent adequate to bend such blank to its fully erected position.

5. A device as claimed in claim 1, in which the lower template unit is provided with a fixedly positioned stop, limiting the rearward movement of the upper section of the body portion of the template unit to an extent approximately 30° out of the plane of the remaining body portion of said template unit.

6. A device as claimed in claim 1, in which the lower template unit is provided with a fixedly positioned stop, limiting the rearward movement of the upper section of the body portion of the template unit to an extent approximately 30° out of the plane of the remaining body portion of

said template unit and means for limiting the forward movement of said upper section of the body portion of the template unit to a position approximately 45° from the horizontal position of the lower body portion of said unit.

5 7. A device as claimed in claim 1, including means upon the upper template unit limiting the movement of the two body portions thereof about their intermediate transverse hinge to a degree approximately 30° from the plane of the horizontal body portion of said unit.

15 8. A device as claimed in claim 1, in which each of the template units is provided with co-operating guide elements automatically positioning the two units when superimposed with the blank therebetween, with their edges in substantial alignment.

20 9. A device as claimed in claim 1, in which the lower template unit is provided near its upper edge with a horizontally extending slot, the edge of the material defining the upper edge of such slot being bent slightly downwardly and backwardly to constitute a frictional engagement for the upper edge of a blank positioned upon such lower unit.

25 10. A device as claimed in claim 1, in which the lower template unit is provided near its upper edge with a horizontally extending slot, the edge of the material defining the upper edge of such slot being bent slightly downwardly and backwardly to constitute a frictional engagement for the upper edge of a blank positioned upon such lower unit, the material forming the lower edge of said slot being similarly bent downwardly and backwardly to permit the ready insertion of the blank under the frictional engagement, said frictional engagement, due to its bent back position, permitting a sliding movement of the blank upon the lower unit when the upper template unit is superimposed thereupon and the template mechanism is operated to break the cut and scored blank.

30 11. A device as claimed in claim 1, in which the lower template unit is provided near its upper edge with a horizontally extending slot, the edge of the material defining the upper edge of such slot being bent slightly downwardly and backwardly to constitute a frictional engagement for the upper edge of a blank positioned upon such lower unit, the material on each side of said downwardly and inwardly bent edge of such slot constituting abutment stops for the blank positioned upon the lower template unit.

35 12. A device as claimed in claim 1, including a scaffold and counterweight arrangement, said scaffold having a horizontal section supporting the two template units in their operative position upon the blank, and a vertical section within which is suspended a counterweight connected by a pair of cords to the upper movable unit and effective to support said unit by means of said counterweight above said lower template unit.

40 13. A device as claimed in claim 1, including a scaffold and counterweight arrangement, said scaffold having a horizontal section supporting the two template units in their operative position upon the blank, and a vertical section within which is suspended a counterweight connected by a pair of cords to the upper movable template unit and effective to support said unit by means of said counterweight above said lower template unit, the cords from said counterweight being anchored to said top template unit at points forward of its horizontal hinged element.

45 75 14. A device as claimed in claim 1, including

a scaffold and counterweight arrangement, said scaffold having a horizontal section supporting the two template units in their operative position upon the blank, and a vertical section within which is suspended a counterweight connected by a pair of cords to the upper movable unit and effective to support said unit by means of said counterweight above said lower template unit, and means upon said top template unit limiting the hinged movement of its two body sections to obtuse disposition with respect to each other of the two sections of said unit.

15. A device as claimed in claim 1, including a scaffold and counterweight arrangement, said scaffold having a horizontal section supporting the two template units in their operative position upon the blank, and a vertical section within which is suspended a counterweight connected by a pair of cords to the upper movable unit and effective to support said unit by means of said counterweight above said lower template unit, said scaffold having across its bottom section a block limiting the movement of the upper section of the body portion of the lower template unit to an extent approximately 30° from the plane 25 of the lower portion of said template unit.

16. A device as claimed in claim 1, in which hinged smaller flap-like parts provided on the bottom unit of the template mechanism have a contour slightly inside of the outlines of the designs to be formed, and in which the hinged smaller flap-like parts provided in the top unit of the template mechanism have a contour slightly outside of the outlines of the designs to be formed, so that when the two units of the template mechanism are superimposed one upon the other, with a flat blank interposed between them, the hinged smaller flap-like parts of the lower unit pass upwardly through the apertures made in the blank by similar hinged smaller flap-like parts of the blank moving forwardly and upwardly out of their original planes, and so that the combined smaller flap-like parts of the lower unit and the smaller flap-like parts of the blank pass through the apertures made in the upper unit by similar smaller hinged parts in the upper unit, moving forwardly and upwardly out of their original planes, to effect a forming and breaking movement on the blank.

17. A device as claimed in claim 1, including a scaffold and counterweight arrangement, said scaffold having a horizontal section supporting the two template units in their operative position upon the blank, and a vertical section within which is suspended a counterweight connected by a pair of cords to the upper movable template unit and effective to support said unit by means of said counterweight above said lower template unit, the cords from said counterweight being anchored to said top template unit at points forward of its horizontal hinged elements, including a pair of pins extending upwardly from the rear edge of the lower template unit, said pair of pins being effective to limit the upward and rearward movement of the template unit when the front edge of the upper unit is lifted by the counterweight arrangement to an open position in relation to the front edge of the lower unit, and to hold the upper unit slightly above vertical alignment with the lower unit preparatory to the breaking operation while the blank is being inserted between the units, whereby when an upward and forward movement is applied to the upper edges of the superimposed units with the blank interposed between them, the first action is a slight downward movement of the upper template unit away from the pins thereby forcing the blank out from under the frictional arrangement of the lower template unit, and pressing the entire blank firmly to the upper surface of the lower template unit to inaugurate the breaking and forming process.
